(57) CLAIM

I claim the ornamental design for a garment organizer, as shown and described.

DESCRIPTION

FIG. 1 is a front view of a garment organizer.

FIG. 2 is a rear perspective view thereof.

FIG. 3 is a side view thereof; and,

FIG. 4 is a front perspective view thereof.

The broken lines shown represent unclaimed subject matter and form no part of the claimed design.

1 Claim, 4 Drawing SheetsFIG. 1

FIG. 4
